DEFIBERING APPARATUS

Cyrus E. Roberson, Hoosick Falls, N. Y., assignor
to The Noble & Wood Machine Company,
Hoosick Falls, N. Y., a corporation of New York

Application June 28, 1943, Serial No. 492,583

4 Claims. (Cl. 92—20)

This invention relates to the defibration of certain fibrous materials for the purpose of reducing the same to extremely fine substantially uniform fibre sizes (in the order of microns) while simultaneously removing therefrom unwanted particles of foreign matter.

For the purposes of this application I shall discuss my invention in its adaptation to the defibration of asbestos fibres. It will be understood, however, that such treatment is illustrative and not limiting and that the principles of my invention are applicable to the defibration of many other fibres.

Considering asbestos fibres as typical, experience has shown that where such material is used for insulating and like purposes, best results are obtained if the fibre has been reduced to very fine, substantially uniform size. The finer and more uniform the fibre, the better its interlacing action when molded under heat and pressure into slabs or the like, and hence the better its insulating properties.

Another advantage of such fine uniform fibres is that they enable the weight of the slab to be substantially reduced without impairment of its insulating properties.

A further advantage of such fine uniform fibres is that substantially all unwanted particles of foreign materials were removed during the defibring operation, thus assuring a substantially clean final product.

In producing such fine uniform fibres I prefer to proceed as follows:

The raw fibres to be processed, consisting in part of fibre bundles and unwanted particles of foreign matter, are mixed with sufficient water or other suitable liquid vehicle in a charging chest to form a suspension of the desired consistency. This suspension is pumped from the charging chest to a receiving chest by way of a fibre selector which functions both to free a portion of the wanted fine fibres from the mass of entangled fibres and foreign particles passing therethrough and send the same to the receiving chest along with the water of suspension, and to reject a portion of the larger fibres and unwanted particles of foreign matter and remove the same from the system.

When the charging chest has emptied and the receiving chest has filled, the circulation is reversed, and the suspension pumped back to the charging chest by way of the fibre selector. At each pass, a new portion of the wanted fine fibres is freed and a new portion of the unwanted

5 larger fibres and foreign particles is removed from the suspension. These passes are repeated until the suspension eventually contains substantially only the wanted fine fibres which are then withdrawn from the system, into any suitable collection receptacle, for such additional processing as may be necessary to adapt them for their intended purpose.

In addition to its fibre-selecting function the 10 selector also exerts a grinding action on the fibres as they are repeatedly passed therethrough. This further reduces the fibres in size and assures a final product in which the fibres are all of substantially uniform size.

15 In the accompanying drawing:

Fig. 1 shows diagrammatically a preferred form of apparatus for the practice of my invention.

Fig. 2 is a fragmentary detail of the fibre selector, and

20 Fig. 3 shows a modification.

In such drawing, the charging chest is indicated at 10 and the receiving chest at 11. Both chests are of substantially equal capacity and each is equipped with any motor-driven agitator 25 12 of well known type.

Chests 10 and 11 are connected to each other near their lower ends by a header 13 equipped with valves 14 and 15. Said chests are connected to each other near their upper ends by a header 16 equipped with valves 17 and 18, and also by means of an overflow pipe 19 equipped with valves 20 and 21.

Header 13 connects at 22 with the inlet side of 30 a motor-driven circulating pump 23 of well-known type. Extending from the outlet side of said pump is a delivery pipe 24 emptying at its upper end into a head box 25. Box 25 is located at such an elevation with respect to the chests as to provide the required static head for a fibre selector indicated generally at 26 disposed beneath said box but above the chests. Box 25 is partitioned as at 27 to form an overflow compartment 28.

35 The capacity of pump 23 is somewhat in excess of the quantity of the suspension which will pass through selector 26. The entire suspension however is pumped into head box 25 and overflows into compartment 28. Such of it as the selector 40 will handle at any one pass flows by gravity through pipe 29 into the inlet side of the selector. That portion of the suspension which is allowed by the selector to pass through it flows to chest 11 by way of pipe 30 connecting with header 16. That portion of the suspension which is rejected

by the selector is discharged out of the system through a suitably valved discharge pipe 31. The surplus portion of the suspension in head box 25 overflows into pipe 32 leading from said box and connecting with overflow header 18.

The fibre selector is preferably of the type disclosed in the patent of James T. Coghill, No. 2,325,159, dated July 27, 1943. Where so constructed, it comprises a chamber 33 (see Fig. 2) into which pipe 28 discharges. One wall of said chamber has an annular opening 34 therein. Secured about said opening is an annular doctor plate 35 having a conical bore to cooperate with the conical surface of a frusto-conical rotor 36 set therein and functioning as a closure for said opening 34. Rotor 36 is fast on a motor-driven shaft 37 operating at suitable speed.

The body of the rotor projects into the suspension and is provided with a plurality of suitably spaced extremely fine alternating ribs 38 and 20 grooves 39. The inner ends of the grooves are disposed interiorly of the chamber and the outer ends of the grooves are disposed exteriorly of the chamber so that in the operation of the selector a portion of the suspension which has entered said grooves by the force of the static head of the suspension and there subjected to centrifugal force is caused by the disposition of the grooves to move outwardly therealong and to discharge exteriorly of the chamber into pipe 30.

The fibres and other particles of foreign matter in the suspension which are of a size as not to be accepted by the grooves are passed out of the selector through pipe 31 and discharged into any suitable collection receptacle (not shown).

The preferred method of operating my equipment is as follows:

After a measured quantity of raw asbestos or other fibres and water has been placed in charging chest 10 and mixed together by means of the agitator 12 in said chest, the several valves of the apparatus are adjusted to permit the suspension to be pumped from said chest to receiving chest 11 by way of the fibre selector. For this purpose, valves 14, 18 and 20 are opened and valves 15, 17 and 21 are closed.

The motors for the circulating pump and fibre selector are started and the suspension from chest 10 is drawn through open valve 14 along header 13 into the inlet 22 of the pump 23. From pump 23 it is pumped through delivery pipe 24 into the main compartment of head box 25, overflowing into the overflow compartment 28, from whence it passes by pipe 29 into the selector chamber 33 and is separated, the fines being passed by means of pipe 30 into header 16 and through open valve 18 into chest 11, the rejected fibres escaping from the system through pipe 31. The surplus portion of the suspension in head box 25 overflows into pipe 32 and passes through open valve 20 back to chest 10 by way of overflow header 18.

When chest 10 is emptied, the setting of the valves is reversed and the suspension is re-passed through the fibre selector from chest 11 to chest 10. This action is repeated until the fibre suspension has been processed to the desired point whereupon the valves are manipulated to permit the suspension to be withdrawn from the head box through valved discharge pipe 40 into any suitable mixer 41 for accomplishing such further processing of the fibres as may be desired.

In order to obtain a more progressive separation of the fibres, I may if desired, construct the fibre selector as shown in Fig. 3. Referring to

this figure, it will be seen that I have provided a plurality of superimposed doctors 35 separated by spacers 35' of such length as to leave pockets 35a between their inner ends and the adjacent face of the rotor 36. The fibres withdrawn from the suspension in selector chamber 33 enter the several pockets 35a, and change direction before discharging into pipe 30. This gives an improved fibre-refining action and reduces the number of times necessary to pass the material from one chest to the other.

Various other modifications in the method and apparatus may obviously be resorted to if within the limits of the appended claims.

What I therefore claim and desire to secure by Letters Patent is:

1. Apparatus of the class described, comprising a charging chest and a receiving chest between which a suspension of fibres is to be circulated, a header connecting said chests near their lower ends, valves in said header for controlling the passage of the suspension from one chest to the other, a circulating pump having its inlet side connected to said header between said valves, a delivery pipe at the discharge side of said pump, a second header connecting said chests near their upper ends, valves in said second header for controlling the passage of the suspension from one chest to the other, a head box surmounting said chests into which said delivery pipe discharges, a fibre selector between said chests, a feed pipe from said head box to the inlet side of said fibre selector, a pipe from the outlet side of said fibre selector connecting with said second-named header between the valves thereof, and a discharge pipe from said selector for withdrawing from the suspension unwanted fibres and foreign matter and discharging the same from the system.

2. The apparatus of claim 1, the head box being sub-divided into a main compartment and an overflow compartment, the delivery pipe from the pump discharging into said main compartment and the feed pipe to the inlet side of the fibre selector connecting with said overflow compartment, an overflow pipe from said main compartment connecting with both of said chests near their upper ends, and valves in said overflow pipe for controlling the passage of the overflow to a selected chest.

3. The apparatus of claim 1, the fibre selector including a frustoconical rotor and a plurality of superimposed doctors surrounding the same, the doctors being separated by spacers of such length as to leave pockets between their inner ends and the adjacent face of the rotor.

4. Apparatus of the class described, comprising a charging chest and a receiving chest between which a suspension of fibres is to be circulated, a head box surmounting said chests and a fibre selector between said chests, means for alternately circulating the suspension from one chest to the other by way of said head box and fibre selector, a header connecting said chests near their upper ends, valves in said header, a feed pipe from said head box to the inlet side of said fibre selector, a pipe from the outlet side of said fibre selector connecting with said header between the valves thereof, and a discharge pipe from said selector for withdrawing from the suspension unwanted fibres and foreign matter and discharging the same from the system.

CYRUS E. ROBERSON.
